UNITED STATES PATENT OFFICE.

KENWRICK CECIL COX, OF NORFOLK ISLAND, SOUTH PACIFIC.

MOVING COIL RELAY.

1,427,093.

Specification of Letters Patent. Patented Aug. 29, 1922.

Application filed September 17, 1917. Serial No. 191,889.

To all whom it may concern:

Be it known that I, KENWRICK CECIL Cox, a subject of His Majesty the King of England, and resident of Norfolk Island, South Pacific, have invented certain new and useful Improvements in or Relating to Moving Coil Relays, of which the following is a specification.

This invention relates to relays of the suspended moving coil type and has for its object to provide an improved relay of the aforesaid type which is more especially intended for use with a selenium or equivalent magnifying apparatus.

According to this invention the relay comprises a suspended moving coil and means to prevent displacement of the coil other than that due to signalling and adjustment. The suspended moving coil is adjusted by means of a pivoted spring so as to control the tension on the coil, and the contacts are disposed on a pivoted block so that the said contacts can be readily moved away from the contact tongue, there being also provided means to prevent sparking between the contact points.

I will describe with reference to the accompanying drawing a construction in accordance with the present invention but I do not limit myself to the precise details of construction described and illustrated.

The drawing is a perspective view of a relay in accordance with the present invention.

Referring to the drawing it will be seen that the wires 27 by which the coil 26 of the relay is suspended are attached at their upper ends to any suitable head for adjusting their positions, such as is commonly used in siphon recorders, but I prefer to use a head such as that described in the specification of U. S. application Ser. No. 181462/15 and which is therein used for suspending the coil of the galvanometer. The lower end of the coil 26 is attached by a thread, wire, or strip 28 to one end of a spring 76 the other end of which is arranged to pivot on a pin 77 or similar arrangement. The tension of the spring is adjusted by means of the milled screw 73 which presses down on the spring, or on the block 78 which may be conveniently arranged to hold the said spring. The moving tongue 31 is mounted as shown, on a strip 79 which is kept under tension, in the same manner as the wire on which a recorder siphon is usually suspend-

ed, by means of a spring 80 and screw 81. The tongue 31 is connected to the coil 26 by wires or threads 30 so that the tongue 31 moves, or oscillates, with the coil. For the satisfactory working of the tongue against the contacts 32 and 33 it is necessary that the wires 30 from the coil should be quite taut. This would ordinarily pull the coil 26 forward considerably, the extent to which it is pulled forward depending on the tension put on the said wires 30 and the tension on the suspending wires 27 and strip 28. This pulling of the coil out of its proper position may be very objectionable, and to prevent it I attach another thread or wire 82 to the centre of the clip 83 which holds the top of the coil 26 in order to hold the coil back against the tension of the wires 30. This additional thread is conveniently led through a hole in the back of the suspension frame and secured to any suitable arrangement for adjusting its length. This adjustment may be effected by means of a screw, or by wrapping the thread round a small rod or roller, 84, the thread being wound more or less round the rod as it is turned in a suitable holder. This thread is attached to the coil, as shewn, at a point on its axis of movement so that the thread does not interfere with the movement of the coil, and it is so placed on this axis of movement as to exactly counteract the tension of the wires 30 without in any way pulling the coil 26 out of its true position as fixed by the suspending wires 27 and the strip 28. With the arrangement described the tension of the said wires 30 may be such as to pull the strip 79 considerably out of the straight line. There is no objection to this, and the arrangement ensures the free and sharp action of the coil 26 and tongue 31 which is necessary for satisfactory working.

Instead of making the part 85 on which the spring 76 is mounted, solid with the suspension frame as shewn, I may make the position of the part 85 adjustable with regard to the main part of the frame so as to provide a convenient means of adjusting the position of the lower end of the coil 26 if required.

In the working of the moving tongue 31 of the relay B between its contacts 32, 33, it is necessary to eliminate sparking at the points of contact. This is effected, for practical purposes by means of two small condensers 87, 88, and a low resistance 89,

arranged as shewn in the drawing with respect to a second relay apparatus C and batteries 39, 34. The relay as shown in the drawing may be applied to submarine cable apparatus in combination with a selenium cell apparatus and a second relay C, the reference numerals 90, 91, 92 in the figure indicating the terminals of the first relay. In this arrangement connection is made to the moving tongue 31 through the strip 79 and the framework of the instrument. Under certain conditions, such as when the relay B is used for simple Morse working, one only of the two contacts 32, or 33 may be required, and in that case only one condenser is necessary. For instance, if the movement of the tongue 31 against one of its contacts 33 is utilized to actuate any given apparatus, the corresponding condenser 88 only is required; the resistance 89 may in such a case be inserted either as shewn between the condenser 89 and the tongue 31 or between the said condenser 89 and the said contact point 33. Again, where both the contacts 32 and 33 are in use, I may use two resistances, one between the condenser 87 and the contact point 32, and the other between the other condenser 88 and the other contact point 33, instead of the one resistance between the condenser and the tongue; or again, I may use two such resistances in addition to the single resistance between the two condensers and the moving tongue.

35 The brass pieces 93, 94 which carry the contact screws 32, 33, are mounted, as shewn, on a block 95 which is arranged to swing round into a position as indicated by the dotted lines in order to move the contact points clear away from the tongue when required. A suitable stop screw 96 is arranged so that the block 95 is always brought back into correct position with regard to the tongue 31. The block 95 is mounted, as shewn, on a slide which is so arranged that the two contacts 32, 33, may be adjusted equidistant from the moving tongue 31, or one or other of them nearer to the tongue, as required, by means of the stop and adjusting screw 96^a.

What I claim is:—

1. In a relay having a movable coil, means for flexibly suspending said coil, a movable contact tongue connected with the movable

coil, and means connected to the movable coil to prevent displacement thereof by the connections between the movable contact tongue and the movable coil.

2. In a relay having a movable coil and a movable contact tongue, means for adjustably and flexibly suspending said coil, taut means connecting the movable contact tongue with the movable coil, and adjustable means connected with the movable coil to prevent displacement thereof by the connections between the movable coil and the movable contact tongue.

3. In a relay having a movable coil and a movable contact tongue, means for suspending said movable coil, taut means, extending substantially at right angles to said suspending means, for connecting said coil and said contact tongue, and relatively taut adjustable means, extending substantially in the reverse direction to said first-mentioned taut means, connected to said coil to prevent displacement thereof by the first-mentioned taut means.

4. In a relay having a coil movable about a central axis and a movable contact tongue, means for suspending said coil, taut means extending substantially at right angles to said axis, for connecting said coil and said contact tongue, and relatively taut adjustable means, extending substantially in the reverse direction to said first-mentioned taut means, connected to said coil at a point on said axis to prevent displacement thereof by the first-mentioned taut means.

5. In a relay having a movable coil, means for supporting said coil, and means for varying the tension of said supporting means, comprising an adjustable block pivoted at one end and a flexible member mounted on said block and engaging said supporting means.

6. In a relay having a movable coil and a movable contact tongue connected therewith, a supporting base mounted beneath said tongue, and a pivoted block having stationary contacts normally in alignment with said contact tongue, mounted on said base and adapted to be swung to one side and thereby move the stationary contacts out of alignment with said contact tongue.

In testimony, hereof I have hereunto signed my name.

KENWRICK CECIL COX.
